(57) **CLAIM**

The ornamental design for a foldable water craft, as shown and described.

DESCRIPTION

FIG. 1 is a front, right perspective view of an ornamental design for a foldable water craft according to the present invention shown in a fully extended configuration;

FIG. 2 is a rear, right perspective view of the foldable water craft of FIG. 1;

FIG. 3 is an enlarged front elevation view of the foldable water craft of FIG. 1;

FIG. 4 is an enlarged rear elevation view of the foldable water craft of FIG. 1;

FIG. 5 is a top plan view of the foldable water craft of FIG. 1;

FIG. 6 is a bottom plan view of the foldable water craft of FIG. 1;

FIG. 7 is an enlarged rear, right perspective view of the foldable water of FIG. 1 shown in a partially folded configuration wherein a portion of the foldable water craft is deflated;

FIG. 8 is a reduced left side elevation view of foldable water craft of FIG. 1 shown in a fully folded configuration;

FIG. 9 is a top plan view of the fully folded foldable water craft shown in FIG. 8; and,

FIG. 10 is a bottom plan view of the fully folded foldable water craft shown in FIG. 8.
